ROLLER FOR TWISTER MACHINES

Clifford H. Wethers, Detroit, Mich.

Application June 15, 1945, Serial No. 599,583

4 Claims. (Cl. 57—90)

1

This invention relates to twister rolls such as are incorporated in the spinning heads of cotton and yarn spinning machines and has for its object to provide in a simple and practical manner for the prevention of the yarn or material being twisted from becoming displaced for any material length of time from the surface of its individual top twist roll and to provide simple means for returning the yarn to the roll surface should it momentarily slip over the end of the roll.

In such machines a number of short upper twist rolls are usually positioned in co-axial arrangement separated by suitable bearings above a lower twist roll, generally of larger diameter, the yarn passing from the creel by way of a water trough over and under these upper twist rolls, then between the upper twist rolls and the lower twist roll and partially around the lower twist roll to guides and thence through the flyers to the bobbins on which the twist yarn is wound. The action of the machine is such that the thread or yarn passing around the said top twist roll wanders in the direction of the length of the roll, toward and from the ends thereof, and it frequently happens that the yarn will travel too far and thus slip over the end of the roll and run on the smaller hub or bearing, thus upsetting the relationship of the yarn feed to the lower twister roll and resulting in a hard twist being imparted to the yarn where the mechanical set-up was arranged to impart a soft twist thereto. This is highly undesirable and its prevention is very important.

The present invention, therefore, proposes to provide a form of upper twist roll which will automatically return the yarn to the periphery of the said roll with a minimum lapse of time whenever the yarn should wander beyond the ends of the roll and tend to fall onto the hub or bearing thereof; and, more particularly, the said invention has for its object to provide in such a roll pick-up fingers or projections at the ends thereof which will immediately intercept any thread or yarn attempting to drop over the end of the said roll and will as a result immediately lift the thread to the level of the roll surface whereupon it can again travel over such surface and between the upper and lower twister roll in the manner intended.

Still further objects or advantages additional or subsidiary to the aforesaid objects, or resulting from the construction or operation of the invention as it may be carried into effect, will become

apparent as the said invention is hereinafter further disclosed.

In carrying the said invention into effect, I may provide each individual upper twister roll of a spinner head with projections extending therefrom and on their outer surfaces form a continuation of the normal peripheral surface of the roll, said projections providing abutment surfaces on to which yarn may descend should it pass over one or other end of the roll, whereby such abutment surfaces will maintain the yarn in temporary alignment with the outer surfaces of the said projection for a sufficient length of time to permit one or other of the projections, 5 as it rotates with the roll, to lift the yarn back to the level of the roll surface and thereby permit it to travel back onto the roll as required. All of which is more particularly described and ascertained, by way of example, having reference to the accompanying drawing, wherein:

Figure 1 is a perspective view of an improved upper twister roll embodying the said invention;

Figure 2 is a similar view of a somewhat modified form of the same;

Figure 3 is a front elevation showing upper and lower twister rolls in relative positions; and

Figure 4 is an end elevation partly in section of the same.

Similar characters of reference indicate similar parts in the several figures of the drawing.

The twisting mechanism of a spinning machine includes a lower twister roll 10 surmounted by a series of upper twister rolls 11 which usually rest upon and are frictionally driven by the said lower roll 10, except that yarn 12 from the creels (not shown) passing over and under each roll 11 and between the said roll 11 and the roll 10 naturally effect a spacing of the rolls 11 and 10 to the extent of the thickness of the yarn. This yarn 12 also passing partially around the roll 10, which is rotated by means well known in the art at a suitably determined speed, passes thence through guides 13 to the flyers and bobbins (not shown) thereby completing the spinning and winding of the thread, technical details of which operation need not be dwelt upon herein as they are quite old and well known in the art to which this invention appertains.

The several rolls 11 are spaced apart in co-axial relation by bearing members 14, and, in the course of the yarn-twisting operation, it often happens that a length of yarn passing over the roll 11 and constantly changing location as to the length of the roll, by reason of the variable manner in which the yarn approaches or leaves

the said roll, passes beyond the extremities of the roll and thus proceeds to travel around the hub 15 or the bearing member 14. This upsets the feed relationship necessary for the maintenance of a constant twist being imparted to the yarn, so that, as long as the condition exists wherein the yarn is so displaced beyond the end of the roll, a hard twist will result where the rolls and twisting mechanism are proportioned and intended to produce a soft twist. If this slippage of the yarn from over the end of the roll is not noticed and immediately corrected and the incorrectly twisted yarn thus permitted to wind to any extent on the bobbin, thread of an uneven and inferior quality is the result.

By my invention I automatically correct such displacement of the yarn by providing on the ends of the roll 11 projections 16 which I prefer to make of arcuate form, as shown in Figure 1, with their outer surfaces 17 being a continuation of the surface of the roll, the ends of the said projection 16 being in the form of abutments 18 extending more or less along chords of the ends of the roll. Thus the said abutments 18 of each projection 16 are in materially spaced relation on opposite sides of a radial plane passing through the abutment and the center of the twister roll.

These rolls revolve quite rapidly and it will be readily apparent from an examination of Figure 4 that if yarn should slip over an end of the roll 11, as indicated in dotted lines of the said Figure 4, it will be caught and held by one of the abutment surfaces 18 of one of the projections 16 in such manner that, as the roll continues to rotate the abutment surface 18 of the other projection on that end of the roll will engage beneath the upper extended length of yarn whereby the continued movement of this projection 16 will lift the yarn back to the position shown in full lines at the top of the said Figure 4.

The outer surface of the said projection 16 is a continuation of the general peripheral surface of the roll so that it thereby encourages the yarn to resume its correct position running over the surface of the roll. The winding motion of the yarn on the roll is such that its tendency to feed beyond the limits of the roll length is more or less momentary whereby this quick lifting of the yarn back to the periphery of the roll will usually suffice to immediately return it to the roll.

In relatively rare cases, where the yarn does not immediately return to its correct running position, it will again and again in rapid succession be subjected to the same lifting action by

the said projections 16 as the roll continues to rotate, so that in any case the amount of time elapsing before the yarn is eventually returned to its correct running position will be very small.

5 The exact form of the yarn-lifting projections or abutments may be varied within the limits of reason; and, in Figure 2, I have shown the ends of the roll as being slotted at 19 in a segmental manner leaving a diametral rib 20 thereon providing lateral abutment surfaces 21, and operating in the manner of the abutment surfaces 18 of the projections 16 previously described. The ends of the said diametral ribs 20 will thus naturally be a continuation of the peripheral surface 15 of the roll.

This invention may be developed within the scope of the following claims without departing from the essential features of the said invention, and it is desired that the specification and drawing be read as being merely illustrative of a practical embodiment of the said invention and not in a strictly limiting sense.

What I claim is:

1. In a twister roll of the type described, projections extending endwise beyond the normal length of the roll, part of the surface of such projections being a continuity of the peripheral surface of the roll, and the spacing between said projections being uninterrupted by the roll proper.

2. In a twister roll of the type described, projections extending endwise beyond the normal length of said roll, said projections having lateral abutment surfaces arcuately extending materially on either side of a radial plane passing through the center of the projection and the center of the roll, and the spacing between said projections being uninterrupted by the roll proper.

3. In a twister roll of the type described, projections extending endwise beyond the normal length of the roll, the outer part of the surface of such projections being arcuate and a continuity of the peripheral surface of the roll, and the spacing between said projections being uninterrupted by the roll proper.

4. In a twister roll of the type described, projections extending endwise beyond the normal length of said roll, said projections having lateral abutment surfaces materially and uninterruptedly spaced on either side of a radial plane passing through the center of the projection and the center of the roll, the outer part of the surface of such projections being arcuate and a continuity of the peripheral surface of the roll.

CLIFFORD H. WETHERS.
